SUMMARY BOARD

George H. Dawson, Chicago, Ill., assignor to Wilson-Jones Company, Chicago, Ill., a corporation of Massachusetts

Original application December 20, 1933, Serial No. 703,176. Divided and this application August 9, 1934, Serial No. 739,072

11 Claims. (Cl. 120—33)

This application is a division of application Serial No. 703,176 filed December 20, 1933, which issued as Patent No. 2,006,795 on July 2, 1935.

This invention relates to a summary board whereby a plurality of sheets may be suspended in horizontal overlapping relationship so that single columns on each of the suspended sheets may be held in juxtaposed positions to facilitate summarization of the data contained in the exposed columns. The invention relates particularly to means for aligning a line guide with reference to the sheets.

It is an object of this invention to provide means for quickly and accurately adjusting the angularity of the line guide, without any need of tools, to insure accurate alignment of the reading edge of the line guide with respect to the sheets suspended in horizontal overlapping relationship. Other objects of this invention will be come apparent upon reading the following description taken in conjunction with the accompanying drawings in which:

Figure 1 is a perspective view of my summary board;

Figure 2 is a fragmentary perspective view illustrating the housing carrying the line guide;

Figure 3 is a top plan view of the housing with parts broken away to facilitate illustration of the structural details;

Figure 4 is a cross sectional view taken along the line IV—IV of Figure 3 looking in the direction of the arrows; and

Figure 5 is a cross sectional view taken along the line V—V of Figure 3 looking in the direction of the arrows.

In the drawings, the reference numeral 2 indicates a flat plate member adapted to be supported at any desired angle by means of an easel structure 3. The preferred easel structure does not constitute part of this invention and is fully described in United States Letters Patent No. 1,883,255 issued October 18, 1932, to Paul O. Unger. The flat plate structure will not be described in detail because it is fully described in United States Letters Patent No. 2,000,558, issued May 7, 1935, to applicant and Paul O. Unger.

The flat plate member 2 is provided with a channel shaped depressed portion 4 adjacent its upper edge. This channel shaped depressed portion 4 is provided with a fixed lug 5 at one end and a slidable lug 6 at the other end and is adapted to receive a ring bar 7 of any suitable design. The ring bar 7 is provided with open ends into which the lugs 5 and 6 are adapted to fit to secure the ring bar in the channel shaped depressed portion 4. The ring bar 7 is adapted to maintain a plurality of sheets 8 impaled thereon in horizontal overlapping relationship.

In order to attain speed and accuracy in computing data from sheets mounted on a summary

board, it is not sufficient merely to have the sheets aligned properly, but it is also necessary to have the line guide parallel with the line of figures being summarized. My line guide mechanism includes a line guide 9 rigidly secured to a housing 10 adapted to travel up and down a rod 11 spaced from one end of the flat plate member 2 and secured in place by a pair of flat strips 12, 13 (Figure 1) extending from one end of the plate member 2 adjacent the top and bottom. The rod 11 is secured to the strips 12, 13 by means of screws or rivets. A portion of the peripheral surface of the rod 11 is serrated, as indicated at 14, Figures 3, 4 and 5.

A metal plate 15, U-shaped in cross section, is mounted in the housing 10 on one side of the rod 11. A pair of rollers 16, 17 is mounted in the plate 15 by means of the studs 18, 19. The periphery of the roller 17 is serrated, as indicated at 20, to enable the roller 17 to mesh with the serrations 14. A pair of coiled springs 21, 22 mounted between the plate 15 and the housing 10 exert a constant force against the plate 15 to maintain the roller 17 in positive engagement with the serrations 14. The springs 21, 22 are positioned by means of the studs 23, 24. One end of the stud 19 is extended beyond the front wall of the housing 10 and carries a knob 25 which may be rotated to move the housing along the rod 11. The aperture in the housing through which the stud 19 passes is slightly elongated, as indicated at 26, Figure 2, for a purpose to be hereinafter described.

A roller 27 is mounted in the housing 10 on the opposite side of the rod 11 by means of a stud 28. A metal plate 29, U-shaped in cross section, is mounted in the housing 10 on the opposite side of the rod 11 from the plate 15 by means of a stud 30. The stud 30 is spaced centrally of the plate 29 so that the plate 29 may be pivotally moved around the stud 30 as a center. Another roller 31 is mounted in the plate 29 adjacent its upper edge by means of a stud 32. A threaded stud 33 is rigidly secured to the plate 29 adjacent its lower edge and extends through one wall of the housing 10. A threaded adjusting nut 34 is mounted on the portion of the threaded stud 33 outside of the housing 10.

The angularity of the line guide 9 is adjusted simply by rotating the nut 34. If the free end 50 of the line guide is lower than the end secured to the housing, the nut 34 is rotated so as to move the lower edge of the plate 29 to the left (Figure 3). Since the rod 11 is fixed, the roller 31 cannot move to the right, and since the housing and plate 29 are secured together by the stud 30, the plate 29 acts as a lever of the second class and pulls the upper edge of the housing to the left.

The lower edge of the housing cannot move any substantial distance to the left because the 60

- slot 26 (Figure 2) is elongated only very slightly, and the right end of the slot 26 soon contacts with the stud 19. In view of the fact that the roller 27 is fixed to the housing and cannot move to the right because it is in contact with the rod 11 which is also fixed, the roller 27 acts as pivot point for the housing. The portion of the slot 26 extending to the left of the stud 19 permits the slight movement of the housing with respect to the stud 19 necessary to permit the counter-clockwise pivotal movement of the housing around the roller 27 as pivot. The rigid securing of the line guide to the housing causes the line guide to move angularly with the housing.
- It will be understood that the apertures in the housing through which the rod 11 passes are sufficiently large to allow the slight movement of the housing necessary to adjust the angularity of the line guide.
- The angular movement of the housing and line guide above mentioned compresses the spring 21. When the nut 34 is moved in the opposite direction from that described above, the spring 21 expands and moves the upper edge of the housing to the right (Figure 3). The lower edge of the housing is prevented from moving to the right by the roller 27 which is fixed to the housing and is in contact with the rod 11. Accordingly, the housing is pivotally moved in clockwise direction and the free end of the line guide is moved downwardly. Obviously, the degree of angular movement of the line guide in either direction can be controlled accurately by means of the threaded adjusting nut.
- While I have described my invention with particular reference to its use in connection with a summary board, it will be obvious that the device may be used with any copyholder or reading device where the angularity of the line guide is important. It will also be understood that the description of my device is illustrative, rather than restrictive, as many details may be modified or changed without departing from the spirit or scope of my invention. Accordingly, I do not desire to be restricted to the exact construction described, except as limited by the appended claims.
- I claim:
1. In a summary board, a line guide, a housing carrying said line guide, a rod on which said housing is adapted to travel, a plate member pivoted in said housing, a roller secured to said plate member and adapted to engage said rod to facilitate travel of said housing, and means to move said plate member on its pivot to adjust the angularity of said line guide.
  2. In a summary board, a housing carrying a line guide, said housing being movable along a rod, a roller in said housing fixed with regard to said housing, and means to move said housing and line guide pivotally about said roller.
  3. In a summary board, a flat plate member, a rod mounted adjacent one edge of said plate member, a housing movable along said rod, a line guide secured to said housing, and means to move said housing angularly with respect to said rod to adjust the angularity of the line guide.
  4. In a summary board, a housing mounted adjacent one edge of said board, a line guide secured to said housing, said line guide extending across the front surface of said board, and means

associated with said housing adapted to adjust the angularity of said line guide.

5. In a summary board, a rod adjacent one edge of said board, a housing movable vertically along said rod, a line guide secured to said housing, a plate pivoted in said housing and having one end fixed against transverse movement in relation to said rod, a threaded stud secured to the opposite end of said plate and projecting through one wall of said housing, and means on said threaded stud outside said wall adapted to cooperate with said plate to move said housing angularly with respect to said rod. 5

6. In a summary board, a rod secured adjacent one edge of said board, a housing on said rod, a pair of spring pressed rollers mounted in said housing on one side of said rod, a fixed roller mounted in said housing on the opposite side of said rod, a plate mounted in said housing on the same side of the rod as said fixed roller, a roller 20 secured to said plate, and means to move said last mentioned roller transversely of said housing, the movement of said last mentioned roller causing said housing to move angularly with respect to said rod. 25

7. In a summary board, a flat plate member, a rod adjacent one edge of said plate member, a housing mounted on said rod, a line guide secured to said housing, a thumb screw projecting through one wall of said housing and cooperating with mechanism within said housing to move said housing along said rod, a second thumb screw outside one wall of said housing and cooperating with mechanism within said housing to move said line guide angularly with respect to said flat plate member. 30

8. In a summary board, a plate member adapted to support a plurality of sheets, a housing secured adjacent one edge of said plate member, said housing being movable along a line parallel 40 to said edge of said plate member, a line guide secured to said housing and extending across said plate member, and a screw projecting through one wall of said housing, the inner end of said screw being adapted to cooperate with means 45 within said housing to adjust the angular position of said line guide.

9. In a summary board, a plate member, a rod secured adjacent one edge of said plate member, a housing movable along said rod, a line guide secured to said housing, a roller in said housing fixed against transverse movement relative to said housing and said rod, and screw means to move said housing and line guide pivotally about said roller. 50 55

10. In a summary board, a plate member, a rod mounted adjacent one edge of said plate member, a housing mounted on said rod, a line guide secured to said housing, said line guide extending across said plate member, and means associated with said housing adapted to adjust the angularity of said line guide. 60

11. In a summary board, a housing mounted adjacent one edge of said board, a line guide secured to said housing, said line guide extending across the front surface of said board, and means within said housing adapted to adjust the angularity of said line guide, a portion of said means projecting through one wall of said housing, whereby said first mentioned means 70 may be operated from outside said housing. 65

GEORGE H. DAWSON.
